UNITED STATES PATENT OFFICE.

PHILIP J. MATTERN AND HAROLD N. WALKER, OF OELWEIN, IOWA, ASSIGNEES OF
ONE-THIRD TO EDWARD C. BALLMAN, OF OELWEIN, IOWA.

BASEBALL GAME.

Application filed June 24, 1925. Serial No. 39,310.

The object of this invention is to provide a base ball game having mechanical means by which an actual game of base ball may be played, comprising a novel combination of levers and tension springs, as hereinafter described.

In the drawings,

Fig. 1 represents a plan view of the game board showing different elements in position 10 on the field of play.

Fig. 2, illustrates an elevational view of the pitcher in position on the board and the mechanical parts attached thereto.

Fig. 3 designates an elevational view of 15 the umpire showing the mechanical parts connected thereto.

Fig. 4 represents an elevational view of the batter, with operating parts attached thereto.

Fig. 5 designates an elevational view of 20 the catcher in relation to the operating paddles and funnel.

Fig. 6 illustrates a plan view of a section taken below the board under the pitcher in 25 Fig. 2, showing the lower plate frame and mechanism for operating the pitcher, in assembled relation.

Fig. 7, represents a plan view of a section 30 taken below the board under the batter in Fig. 4, disclosing the lower plate frame and operating mechanism in assembled relation appertaining to the batter.

Fig. 8, shows the plan view of a section 35 taken from Fig. 5, disclosing the paddles in attached relationship to the legs of the catcher.

Fig. 9, represents a slight modification of 40 Fig. 5, a method of running wires from paddle 29 and 30 down through holes in the board 1 and then back to the umpire thereby eliminating the use of spring 58.

Fig. 10, illustrates a dial having a spinner adapted to be used by the player at the bat for base stealing.

Fig. 11, illustrates a dial having a spinner adapted to be used by the player operating as pitcher.

Numeral 1 represents the main game board 50 to which the base ball figures, pitcher 2, batter 3, catcher 4 and umpire 4' are attached, and manipulated by mechanical means comprising, for the pitcher 2, an upper frame plate 5 fastened under the board by means of three screws, posts 6 for frames and lower 55 frame plate 7, the lower and upper frame

plates being fastened together by screws 8. The numeral 9 designates a spindle which is rotatably mounted and extends up through an opening in board 1, and into the upper half of pitcher 2, while 10 is a post dowel 60 from spindle 9, which turns with the spindle and is used to swing back and catch under the trigger 11, when released it will be pulled forward by spring 12, and stop at a point determined by the adjusting screw 13 having 65 locknuts 17. Through the board 1 extends a portion 16 of the trigger 11 adapted to carry a counterbored operating button 14, having an equalizing spring 15 therein. The tension in spring 12, may be regulated by adjusting screw 18, and the locknuts 19. The screw 13 controls the side motion and the screw 18 controls the distance the ball is thrown.

In the case of the batter 3, an upper 75 frame plate 20 is fastened under the game board 1 by means of three screws, and 21 represents the posts for fastening the upper frame plate 20 and lower frame plate 22 together by screws 23. The numeral 24 designates a spindle which is rotatably mounted and extends up through an opening in board 1 and into the upper half of the batter 3, while 25 is post dowled in the spindle and turns with it, and catches under trigger 26, 80 and when released will swing free. The post dowel 25 also tips wire 27 which pushes a flapper 28 over the paddle 29 on the left of the catcher 4. The flapper 28 is hinged to the left side of funnel 31. The paddle on 85 the right side of catcher is represented by numeral 30. The triggers 11 and 26 are fastened to the under side of the board by hangers 32 and 32' and pivot on pins 33 and 33'. Through the board 1 extends a portion 90 35 of the trigger arm 26, adapted to carry a counterbored operating button 34, having an equalizing spring 36 therein.

Numerical 37 designates a spring to operate the spindle 24. The spring 37 is fastened 100 around the spindle through a hole 38, in post dowel 25, and through a hole 39 in the bottom half of frame.

A slide wire 40 extends down through a slot in the board 1 and slides over in front 105 of dowel post 25, thereby stopping the bat directly across home plate, the wire 40, being held in place by hangers.

The wire 27 to operate the flapper 28 on 110 the funnels 31 is held in place by two hang-

ers 41 and 42 attached to board 1 of the game. Near the top of the spindles 9 and 24 are placed pin holes 43 and 44.

The half funnel 31 is fastened to the catcher's arms and legs, with the flapper 28 hinged on the left side to cover the left paddle 29 when the batter strikes, the paddle and flapper being operated by a wire 27 extending to dowel post 25, and forked at 45 and held in place by hanger 41. The numeral 46 designates wires to the umpire from the paddle, while 47 represents the pin through catcher's leg, and 48 is a wire joined to wire 46, and extending up through the 15 umpire's legs to a trigger portion 49, which is joined to 48 and held in place by a pin 50 through the body, catches in hooks 51 in the 20 umpire's hands. Springs 52 and 53 act to force the umpire's arms up when released by trigger 49, the springs are fastened by pins 54, 55, 56 and 57. Coil springs 58 are located at the lower leg portions of the 25 umpire, and act to equalize the trigger portions 49.

25 Fig. 9 of the drawings represents a modified form of connecting the paddle portions 29 and 30 with the umpire 5, which is suitably adapted to function with the funnel portion 31. The leading wires 46 in the 30 modified form being disclosed to extend from the paddles to the umpire underneath the board 1, and adapted to rest on a hanger as at 47, the hanger being located underneath the board 1 in such a manner as to bring a 35 sufficient weight on the extension 48 to pull the catching elements at 51 thereby functioning to operate the umpire as when the paddles 29 or 30 are struck with the ball they will act to release the umpire's arms 40 without the use of tension springs. In order to provide a stop for keeping the ball from rolling back on the field of play without going into the funnel 31, an element is adapted to be located between the paddles 29 and 45 30 of a suitable form to keep the ball from striking both paddles 29 and 30 at once.

50 In operating the game the two dials disclosed in Figs. 10 and 11 may function as follows: The dial disclosed in Fig. 10, is 55 preferably located to the left of the umpire on the board 1, and may be operated by the party at the bat for base stealing. The dial shown by Fig. 11, is preferably positioned to the right of the umpire and may be operated by the party who is operating the pitcher. Suitable means in the form of an extension wire may be provided for operating the pitcher from the side of the board.

56 Numeral 59 is the fence around the out-field spaced off for signs as at 60, while 61 designates pockets counterbored close together and colored to indicate plays. 62 represents sides to keep ball from rolling off board 1.

65 Numerals 63 and 64 show holes for re-

ceiving the spindles 9 and 24 which carry the pitcher's and batter's bodies. The positions of catcher and umpire are located on the board by 4 and 4'. The numeral 67 designates a slot in a board for slide wire 40 adapted to make the batter bunt. 68 is a slot in the board through which the wire extends to operate the flapper 28 on the funnel 31, while numeral 69 designates the pitcher's mound, and 70 the posts for elevating the board above the table to keep the mechanical works clear therefrom. The dials disclosed in Figs. 10 and 11 are designated by numerals 65 and 66. Fig. 11 is adapted to be used by the player acting as pitcher, to catch a player off base, while Fig. 10 is used by the player acting as batter, to advance a man at base.

The pitcher (2), and batsman (4), are cut in sections at (71) and (72). The upper half fastens with pins (43) and (44) through the body portion and spindles (9) and (24). The spindles rotate freely in the lower half which is fastened to board 1.

90 The fence 59 may be made in sections to conform with the design of the board, which may be constructed to fold along sectional lines. L shaped hooks may be fastened in the fence to slide under the wires which are preferably fastened to the edge of the board 95 in the out field.

99 This invention provides a base ball game whereby actual base ball is played. The pitcher throws the ball by means of the first player operating the button 14, usually after being put "out". The batter is operated by the second player, usually described as "going to bat", the button 34 is pressed, and the batter hits the ball if the second player makes him swing in time. Should the batter miss or let a ball go by, the ball will strike in the half funnel and glance down on one of the two paddles 29 and 30, which are located in front of the catcher. The paddles when they are hit by the ball in turn 105 operate the umpire's arms and the umpire will call "ball" or "strike" by raising either right or left arm. The batter may make a "bunt" by means of a slide 40 wire which will operate to hold the bat directly across 110 home plate. Should the batter hit or bunt, the ball will settle in one of the many pockets on the board or field of play, and will, thereby, indicate the nature of the play.

115 In connection with this game there will 120 be, obviously, a book of rules, and chart of pockets on the board and three men for each side at bat to be used as "base runners."

What we claim is:

125 1. A base ball game having a pitcher, batter, catcher and umpire and means for throwing the ball, batting the ball, catching the ball and operating the umpire, the said means consisting of a trigger arm operated through a counterbored push button, there-

by releasing tension springs which function to operate the pitcher, batter, catcher and umpire.

2. In a baseball game requiring players, 5 pitcher, batter, catcher and umpire elements, means for pitching the ball, batting the ball, catching the ball and operating the umpire elements, and means for indicating the result of a throw to base by the pitcher element 10 operated by the player on the pitching side.

3. In a baseball game requiring players, 15 pitcher, batter, catcher and umpire elements, means for pitching the ball, batting the ball, catching the ball and operating the umpire elements, and means for indicating the result of a throw to base by the pitcher element operated by the player on the pitching side, the means for pitching and batting the ball 20 consisting of a tension spring, a trigger arm and push button.

4. In a baseball game requiring players, 25 pitcher, batter, catcher and umpire elements, means for pitching the ball, batting the ball and operating the umpire elements, the means for operating the umpire element consisting of suitably positioned sections comprising paddle portions to receive the ball

and lever elements from the paddle portions to the umpire element.

5. In a baseball game requiring players, 30 pitcher, batter, catcher and umpire elements, means for pitching the ball, batting the ball, catching the ball and operating the umpire elements, and means for indicating the result of a throw to base by the pitcher operated by the player on the pitching side, and means for indicating the result of base stealing 35 operated by the player on the batting side.

6. In a baseball game requiring players, a 40 pitcher, batter, catcher and umpire elements, means for pitching the ball, batting the ball, catching the ball and operating the umpire elements, means for indicating the result of a throw to base by the pitcher operated by 45 the player on the pitching side, and operable means for bunting the ball consisting of a device for holding the bat directly across the plate.

In testimony whereof they affix their sig- 50 natures.

PHILIP J. MATTERN.
HAROLD N. WALKER.
